[57] **CLAIM**

The ornamental design for an automobile grill, as
shown and described.

DESCRIPTION

FIG. 1 is a top, front perspective view of an automobile
grill showing my new design;
FIG. 2 is a front elevational view thereof;
FIG. 3 is a rear elevational view thereof;
FIG. 4 is a top plan view thereof;
FIG. 5 is a bottom plan view thereof; and
FIG. 6 is a right side elevational view thereof, the left
side elevational view being a mirror image of that
shown.

FIG. 1

FIG. 2

FIG.3

FIG.4
